UNITED STATES PATENT OFFICE

HERBERT BARCROFT ODELL, OF TORONTO, ONTARIO, CANADA

TURNSTILE

Application filed December 21, 1928. Serial No. 327,551.

My invention relates to improvements in turnstiles, and one object of my invention is to provide a turnstile which, while it may be used in the ordinary way to control traffic through a given passage, and also to record the volume of traffic, if desired, passing therethrough, may be adjusted so as to offer the minimum of resistance to streams of traffic down each side thereof without requiring the operation of the turnstile, in contrast to the impedance of traffic by turnstiles as now manufactured, in that the common type of turnstile must rotate at all times when traffic passes through the passage in which the turnstile is located, and the result is that traffic cannot pass down each side of this standard type of turnstile in the same direction, as is possible with the subject-matter of the present application; therefore by means of the said invention any given body of people can pass down each side of this turnstile in a common direction, for example, and so vacate any given building or area at much less time than is possible with the old style of turnstile. The foregoing feature is a very important one, also in the case of fire. Another object of my invention is to provide means to permit certain of the arms of the turnstile to be moved independent of the recording action of the turnstile to lie in a position substantially parallel to the passage in which the turnstile is located, in common with the other pair of arms, thereby permitting freedom of passage down each side of the turnstile in the same or different directions. A still further object of my invention is to provide means to prevent any sudden blows against certain members of the arms of the turnstile when these arms are brought to rest by the operator, thus avoiding breakage. A still further object of the invention is to provide means to prevent the backward turning of the turnstile and thus avoid deranging the indicator when same is used with this turnstile. A still

further object of my invention in its most specific embodiment is to pivotally mount the arms of the turnstile in a head rotatably carried by a base or column, and to provide means to permit opposing pairs of arms to be moved independently of the other pair of arms, while at the same time this other pair of arms are locked in position, and in the following specification and the drawings forming part thereof, I shall describe and illustrate one embodiment within my invention, and what I claim as new will be set forth in the claims forming part of this specification.

Fig. 1 is an elevation of a turnstile embodying my invention, showing the parts thereof in position to control the passage of traffic, and Fig. 2 is a plan of my turnstile showing certain of the arms moved in parallel relationship to the fixed arms to permit traffic to pass in the same or opposite directions down each side of the turnstile. Fig. 3 is a vertical central section on the line 3—3, Fig. 1, on an enlarged scale. Fig. 4 is in part, a vertical central section through the head of the turnstile, showing the positions of the upper and lower locking sleeves when it is desired to move the pairs of arms lying substantially at right angles to the direction of traffic through a passage so that they may occupy the positions shown in Fig. 2. Figs. 5 and 6 are horizontal cross sections on the lines 5—5, and 6—6, respectively, Fig. 3. Fig. 7 is a horizontal cross section on the line 7—7, Fig. 4. Fig. 8 is a horizontal cross section on the line 8—8, Fig. 3. Fig. 9 is a plan of the upper locking sleeve, and Fig. 10 is a plan of the underside of a lower head block.

In the drawings, like characters of reference refer to the same parts.

In common with other types of turnstiles, I use a tubular base or column 2 which may be secured in place after any suitable manner. Located axially within the base or

60

70

75

80

85

90

column 2 is a post 3 which extends above said base or column. This post 3 is centrally supported by said base or column 2 after any suitable manner, for example, I show the post as held in bridge pieces 4 which are integrally cast with the base or column 2. The said bridge pieces are centrally bored axially with the base or column 2 to receive the post 3, and any suitable means such as a pin 5 may be passed through the lower bridge piece and into the post 3 to removably hold it in position.

The head of the turnstile is composed of the following elements: 6 is a centrally-apertured upper head block, and 7 is a centrally-apertured lower head block. As shown in Fig. 3 these head blocks are mounted on the post 3, and are coupled together in spaced relation by a sleeve 8. The ends of this sleeve are secured to the reduced inner portions of the said blocks by any suitable means, such as screws 9 (Fig. 4).

The said head blocks are very similar in construction, and each is provided with pairs of aligned holes which lie parallel to the longitudinal axis of the turnstile, and are located substantially at 90° apart. Obviously said holes in the upper head block 6 are in alignment with the said holes in the lower head block 7, and positioned in these holes are rods 10. The lower ends of the rods 10 are supported in the bottom of the holes receiving same as shown in Fig. 3. The said head blocks are provided with spaced lugs 11 through which the said pairs of holes in the said head blocks pass and in which the rods 10 are located, and positioned between each pair of lugs 11 are the inner ends 12 of the horizontal members 13 of the arms of the turnstile. The upper and lower surfaces of these inner ends 12 are substantially parallel, and they operate in contact with their respective sides of the said lugs. As shown clearly in Figs. 3 and 6, the rods 10 pass through the said inner ends 12 thereby pivoting the arms of the turnstile to said head. It will be understood that the space separating the said lugs 11 forms an annular channel in each of the said head blocks of sufficient size to permit freedom of movement of said arms. 14 is a plate centrally apertured through which the post 3 passes, and this plate is supported by the base or column 2 and is constructed to interfit therewith in any suitable manner so as to be stationary. The preferred construction to hold the plate 14 in fixed relation to the base or column 2 is the provision of dependent lugs 15 which are received by correspondingly-shaped slots 16 formed in the upper end of the base or column 2. For ease of assembly, the plate 14 is made separate to the base or column 2 though it is within the scope of my invention to form

this plate 14 integrally with said base or column.

17 and 18 are upper and lower locking sleeves substantially identical in construction, though one is larger than the other. Each locking sleeve embraces an inwardly-extending tubular member 19; a horizontal flange 20, and a vertical flange 21. Each vertical flange is provided with openings 22 which openings are located to be in alignment with the horizontal members 13 of the arms. Each locking sleeve is also provided with a plurality of pierced lugs 23 through which the rods 10 pass, as shown clearly in Figs. 3 and 4.

The tubular member 19 of each locking sleeve is exteriorly threaded to receive an internally-threaded adjusting sleeve 24 (Figs. 3 and 4). This adjusting sleeve 24 while free to be turned around the vertical axis of the said head is fixed against movement vertically by any suitable means. The preferred means embraces a centrally-apertured plate 25 which surrounds the sleeve 8 and is keyed thereto by any suitable means such as a screw 26. This plate 25 is also provided with a plurality of holes to permit the rods 10 to pass therethrough, and in its perimeter is formed a groove 27 in which is located a ring 28 made of two segments so as to be placed in position. Each segment of this ring is suitably secured to the adjusting sleeve 24 by means of screws 29, and of course is located on the inner side of said sleeve and substantially midway the height thereof. By turning the sleeve 24 the upper and lower locking sleeves 17 and 18 are moved towards each other out of engagement with and above respectively, the horizontal members 13 (Fig. 4) thus permitting of the movement of certain pairs of arms of the said turnstile into the position shown in Fig. 2, for the purpose already mentioned. By reversing the movement of the said adjusting sleeve, the said locking sleeves are moved back to normal position: this return movement of course cannot be given these sleeves until the arms of the turnstile occupy the positions shown in Fig. 1.

30 is a cap plate which is keyed to the upper end of the post 3 by means of a pin 31, or otherwise, and this cap plate is suitably constructed to house a flanged plate 32 which is centrally apertured to pass over the upper end of the post 3. The flanged plate 32 rests in contact with the upper end of the upper head block 6 to which it is secured by any suitable means such as the screws 33. This flanged plate forms part of a register, but as the same does not form part of my invention, I do not find it necessary to further illustrate it. Various types of registers for the purpose in question are in use. This register is provided with a

cover 34 suitably secured in place to the cap plate 30, and this cover has a slot 35 to permit the register to be seen. As before-mentioned, I do not confine myself to using a register.

Suitable clutch means of course must be employed to prevent substantial movement of the turnstile backwards, as when a register is used this backward movement would interfere with the correct recording of traffic. The type of clutch I illustrate for this purpose is well-known, and it embraces the plate 14 which is provided with a flange 36 which is provided on its inner side with a ratchet 37. A plate 14' is located within the flanged plate 14 and it is provided with studs 38 located substantially at 180° apart, and on each of these studs is mounted a pawl 39. The tail 40 of each pawl normally rests in slots 41 formed in opposite sides of the boss 42 which forms part of the lower head block 7 and projects below the same. As shown clearly in Figs. 3 and 5 the post 3 passes through said boss and through the plate 14'. When the parts are in the positions shown in Figs. 1 and 3, sufficient movement of the arms of the turnstile backward will cause the head of the turnstile to turn sufficiently to cause the boss 42 to move the pawls 39 into contact with the ratchet 37 and prevent further backward movement, as shown in Fig. 5. Movement given to the head of the turnstile in a proper direction will cause the boss 42 to move the pawls 39 out of contact with the ratchet 37, the releasing movement of said pawls being limited by the studs 43 carried by the plate 14'.

Embraced in the said head of the turnstile are four pins 44 located substantially at an angle of 90° to each other, and each pin is mounted in a pocket 46 formed in the central portion of the lower head block 7, and the axis of each of these pockets is in alignment with the longitudinal axis of the lower horizontal members 13 of each arm of the turnstile. These pockets 45 open into the annular space separating the lugs 11 of said lower head block. Formed in opposite sides of the post 3 are two pockets 46, and these pockets are in alignment with any given pair of pockets 45. Upon referring particularly to Fig. 6; it will be noticed that the line 47 represents a radius greater than the line 48. Therefore if the horizontal pins 44 in Fig 6 be in alignment with the pockets 46, obviously if the members 13 shown in horizontal position in Fig. 6 be moved in the directions indicated by arrows, the lower corners 49 of these horizontal members by reason of their greater radius will force the horizontal pins 44 inwardly into the pockets 46 to permit the clearance of said corners with said pins so that the pairs of arms under consideration may be moved into the position shown in Fig. 2. By reason of the

fact that there are only two pockets 46, the pins 44 shown in vertical position in Fig. 6, will be in contact with the imperforate surfaces of the post 3, and consequently the horizontal members 13 shown in vertical position in Fig. 6 because of the greater radius of their corners cannot have movement by their associated pins 44, and consequently the horizontal normally-positioned pairs of arms illustrated in Fig. 2 are locked against movement, of any consequence.

Clearly the movements of the members 13 shown in horizontal position in Fig. 6 cannot take place until the adjusting sleeve 24 has moved the upper and lower locking sleeves 17 and 18 out of their path of movement as illustrated in Fig. 4.

Any suitable type of locking means may be employed to limit the movement of the arms of the turnstile. As is well-known the arms of this type of device are moved through an angle of 90° to permit one person to pass, and when this person has passed it is usual to employ means to prevent the passage of another person until his fare has been paid. The locking means I illustrate is well-known, and embraces a locking arm 50 which is suitably pivoted within the base or column 2. The upper end of this locking arm normally operates in a slot 51 which is formed in a projection forming part of the plate 14. In this position the locking arm is obviously in the path of movement of the lowermost horizontal member of one of the arms, and ordinarily this horizontal member would come in contact with this locking arm. By reason of the pivotal mounting of the arms of my turnstile, I find it advisable to provide sturdy means forming part of the lower head block 7 to receive the blow of the head of the turnstile developed by contact with the locking arm 50. This means comprises four lugs 52 which are substantially at 90° apart, and they project beyond the main body of said lower head block as shown clearly in Fig. 10, and are located underneath the normal positions of rest of the lower horizontal members. When the locking arm 50 is thrown into the path of movement of any given arm, it will also be in the path of movement of one of the lugs 52 (Fig. 10), and consequently these lugs in turn will receive the impact of the blow. There is always a slight movement possible to the arms of my turnstile, and any blow they may receive by contact with the arm 50 will be very slight.

The locking arm 50 is coupled by a rod 53 to the foot trip 54, and by means of the spring 55 coupled at its upper end in any suitable way to the base or column 2, and at its lower end to the foot trip 54, the locking arm 50 is automatically returned to nor-

mal position when pressure against said foot trip is removed.

While I have described what I consider to be the best embodiment of my invention, 5 I desire it to be understood that the principle can be embodied in many different forms and I desire not to be limited beyond the requirements of the prior art and the terms of my claims.

10 What I claim as my invention is:

1. A turnstile comprising a stationary vertical support; a vertical head revolvably carried thereby; two opposing pairs of horizontal arms; vertical means lying substantially parallel to said support and carried by said head and on which the inner ends of said arms are pivoted, said pairs of arms being mounted so as to be given a common rotary movement with said head 15 around said support; means to lock said head and arms against said rotary movement, and means interiorly carried by said head and functioning directly in conjunction with said stationary support to release 20 one pair only of said arms in opposing position so that they may be swung horizontally on their vertical pivotal means while said head is locked against rotation to place them substantially parallel to the direction of 25 movement of traffic through the passageway in which said turnstile may be located.

2. In the combination as set forth in claim 1, the further feature of providing means to lock said vertical head against any material reverse movement.

3. A turnstile comprising a stationary vertical tubular support; a post fixedly centrally mounted within said support and projecting thereabove; a rotary head 40 embracing upper and lower head blocks through which said post passes; vertically apertured horizontally-disposed lugs carried by said head blocks, located respectively substantially at an angle of 90° to one 45 another and in the same horizontal plane; a sleeve located around said post and secured at its upper and lower ends to said head blocks; rods mounted in said lugs exteriorly of said sleeve; horizontal arms grouped in 50 pairs in opposing position and pivoted at their inner ends on said rods; means carried by said head whereby the said arms and head may be given a common rotary movement on said post; opposing pairs of pins 55 loosely mounted in pockets formed in one of said head blocks and normally lying in the same plane as the inner pivoted ends of said arms, one pair of opposing pins located opposite pockets formed in opposite 60 sides of that part of said post located within said particular head block so that as the arms of a given pair in opposing position are moved on their respective rods their ends in contact with their associated pairs of pins 65 will force these pins into their respective

pockets and said given pair of arms may then be moved to ultimately occupy positions parallel to the direction of movement of traffic.

4. A turnstile comprising a stationary vertical support; a post fixedly centrally mounted therein and projecting thereabove; a rotary head embracing upper and lower head blocks through which said post passes; vertically-apertured lugs carried by said head blocks located respectively substantially at an angle of 90° to each other and in the same horizontal plane; means coupling said head blocks together; two opposing pairs of horizontal arms; vertical rods 70 lying substantially parallel to said post and mounted in said lugs, and on which the inner ends of said arms are pivoted; means carried by one of said head blocks and positioned intermediate the inner ends of said pairs of arms; and said post, and adapted, when so set, to be moved into pockets formed in said post to provide for movement of one pair only of said arms in opposing position, on their associated rods, for the purpose specified; upper and lower locking sleeves mounted on said rods and adjacent each of the said head blocks; each sleeve having openings through which said arms extend; an internally-threaded adjusting sleeve having threaded engagement with the inner ends of said arms are pivoted; means fixedly carried by said rods and coacting with said adjusting sleeve and around which the latter has rotary movement so as to move 75 said locking sleeves towards or away from each other so that they may be moved out of, or into, the path of movement of said pairs of arms when it is desired to permit the arms of one pair to be swung upon their pivotal points independently of rotary movement of said head, or to cause said pairs of arms to have common rotary movement with said head.

5. In the combination as set forth in claim 4, the further feature of providing a fixed plate at the upper end of said support against which said lower head block rests; means coacting with said plate to limit the recording movement of the arms of said turnstile, and lugs forming part of said lower head block and projecting therebeyond and adapted to contact with said movement-limiting means, for the purpose specified.

6. In a turnstile, in combination a vertical base; a vertical fixed post centrally carried thereby and projecting thereabove; a head block rotatably mounted on said post and provided with vertically-apertured horizontally-disposed lugs located substantially at an angle of 90° to one another; means carried by said base to lock said head block against material reverse movement; vertical rods mounted in said lugs; horizontal arms 120

grouped in pairs in opposing position and pivoted at their inner ends on said rods, and opposing pairs of pins loosely mounted in pockets formed in said head block and
5 normally lying in the same plane as the inner pivoted ends of said arms, one pair of opposing pins located opposite pockets formed in opposite sides of that part of said post located within said head block so that
10 as the arms of a given pair in opposing position are moved on their respective rods their ends in contact with their associated pair of pins will force these pins into their respective pockets and said given pair of arms may
15 then be moved to ultimately occupy positions parallel to the direction of movement of traffic.
